DESIGN FOR A POWER-LIFT ATTACHMENT FOR TRACTORS

Wayne W. Simmonds, Ottawa, Kans., assignor to
Ottawa Steel Products, Incorporated, Ottawa,
Kans., a corporation of Kansas

Application June 11, 1945, Serial No. 120,002

Term of patent 14 years

(Cl. D14—3)

To all whom it may concern:

Be it known that I, Wayne W. Simmonds, a citizen of the United States and a resident of Ottawa, county of Franklin, State of Kansas, have invented a new, original, and ornamental Design for a Power-Lift Attachment for Tractors, of which the following is a specification, reference being had to the accompanying drawings, forming a part thereof.

In the drawings:

Figure 1 is a perspective view taken from a

position in front of and to one side of a power lift attachment for tractors, embodying my new design, the dotted lines being used for illustrative purposes only; and

Figure 2 is a similar perspective view of the opposite side of said attachment.

I claim:

The ornamental design for a power-lift attachment for tractors, as shown and described.

WAYNE W. SIMMONDS.
